UNITED STATES PATENT OFFICE.

LEWIS A. MAYALL, OF PHILADELPHIA, PENNSYLVANIA, ASSIGNOR TO NATIONAL METAL EDGE BOX COMPANY, A CORPORATION OF PENNSYLVANIA.

MACHINE FOR CREEASING CARD OR OTHER BOARD FOR BOX-MAKING.

1,126,816.

Specification of Letters Patent.

Patented Feb. 2, 1915.

Application filed June 1, 1914. Serial No. 842,048.

To all whom it may concern:

Be it known that I, LEWIS A. MAYALL, a citizen of the United States, residing at the city of Philadelphia, in the county of Philadelphia and State of Pennsylvania, have invented certain new and useful Improvements in Machines for Creasing Card or other Board for Box-Making, of which the following is a specification.

10 My invention has relation to a machine to automatically by a sequence of operations upon a sheet of card or other board form creasings for being then bent into a unit-structure; and in such connection my said 15 invention relates to the constructive ar- arrangement of the different mechanisms in such a machine for the defined purpose.

Hitherto it has been the general practised 20 method in the making of creased sectional sheets to become box-like structures to first crease one side of the sheet or board, then to shift the sheet or board, to crease the opposite side and then to perform the same 25 action in respect to the creasings of the ends; but according to my present invention 30 the entire operations of forming creases in the ends and sides of the sheet or board are conducted automatically in the machine by a sequence of following operations per- 35 formed upon the sheet or board without change of direction of the travel of the board in respect to its plane of travel through the machine, that is, the sheet or board is fed into the machine at one end 40 and turned out at the other end creased on two ends and sides, without manual han- 45 dling during its momentary travel through the machine to complete the creased sec- tional structure ready for being formed or bent into the desired shape or configuration for use, as a unit section of a package holder or container.

My invention consists of a machine such as hereinafter more fully described and 45 claimed.

The nature and scope of my present in- 50 vention will be more fully understood from the following description taken in connec- tion with the accompanying drawings form- ing part hereof, in which—

Figure 1, is a longitudinal side elevation of an automatic machine of my invention, found practically efficient and embodying the essential main features of my said in-

vention. Fig. 2, is a top or plan view of 55 the product of said defined mode, showing how the board is creased first in one end and then in the opposite end, and then by a sequence of following operations in two sides; this view showing also by the arrows 60 how the sheet or board passes automatically through the machine to be acted upon through said sequence of following operations upon the said board, for creasing the same, without the machine shifting or 65 changing its plane of momentary travel to complete such creasings thereof, until dropping from the machine ready without further manipulation to be bent up along the creasings as shown, into an oblong box- 70 like unit section to provide ultimately with a similar sectional unit a package holder or container. Fig. 3, is an enlarged detail view in broken sectional elevation of the stop- 75 operating mechanism located at the rear of the machine, to position received board during the formation of the side creases there- in. Fig. 4, is a longitudinal central section view of the machine, parts thereof in this view, being shown in elevation. Figs. 5 and 80 5^a, are broken sectional plan views of the machine, partly in section, to disclose re- spectively detail arrangements of several different mechanisms of the machine. Fig. 6, is a front elevational view of the main 85 operating mechanism of the said machine. Fig. 7, represents in section and in elevation the constructive arrangement of the plunger creasing devices of the machine. Fig. 8, is an enlarged view of one of the plunger 90 creasing devices, showing the character of the creasings of the board by such devices, shown in action on the board and the par- ticular character of creasing at corners in 95 particular, for permitting of the subsequent free bending of the body into required shape, without breaking the fibers of the said corners in the bending of the said board. Fig. 9, is a side elevation of the char- 100 acter or shape of creasings finally derived and in manipulating thereafter it will readily yield to any bending along the line of such creasings, without breaking the fibers of the board in order to assumeulti- 105 mately the form or shape of the unit section of a holder or container required which if otherwise, would appreciably weaken the creased structure at such points in assuming

its final shape or form. Fig. 10, is an enlarged detailed elevation and section of the mechanism to permit of the release of the board so as to be fed to receive in sequence 5 therein the respective end creases. Fig. 11, is a view in sectional elevation of the preferred arrangement of one of the series of guide-rolls of the machine for guiding the board in its travel through the machine to 10 be subjected to the series in sequence of aforesaid following operations; and Figs. 12, 13 and 14, are respectively, enlarged sectional elevations of certain stop-devices illustrated in detail as employed in the said 15 machine.

Referring to the drawings, A and A¹, are the standards of the machine supporting the several different operative mechanisms thereof and a and a¹, are respectively, the feed and discharge tables carried by the said standards, as clearly illustrated in Figs. 1 and 4. The feed table is provided with an adjustable guide a², as shown in Fig. 5, for 20 positioning the sheet or board to be fed 25 unto the machine.

The paper being thus positioned as above, is fed crosswise of the table a, against stops a³ and a⁴, located in brackets a⁵ and a⁶, carried by the creasers C and C¹. The paper is 30 fed under guides a⁷, Fig. 5, into contact with revolving feed rolls a⁸, journaled to a cross-shaft a¹⁰, positively driven by a gear-means to be presently fully explained. On rock-shafts b, at the front and rear of the machine are secured pressure-rolls b¹, for pressing the sheet or board against the rolls a⁸, so as to feed the sheet or board forward 35 against stops a¹¹ and a¹² when the said sheet or board is released by the stops a³ and a⁴, to bring the said sheet or board into a true alining position to be acted upon by following operations of creasers C and C¹. These creasers are located on both sides of 40 the center line of the machine and consist of male and female members c and c¹. The male member is provided with a T-shaped bar c², the leg of which is recessed to receive a coiled spring c³ bearing against a T-shaped disk c⁴, carried in suitable guides 45 c⁵, which latter are bolted to the leg of the T-bar c², as clearly shown in Fig. 7. The female member c¹, consists of a channel bar c⁶, in which is mounted an anvil c⁷, supported in position by means of coiled 50 springs c⁸ and c⁹, forming as so arranged a cushion for said anvil. The plunger c¹⁰, of the female member is journaled in the anvil c⁷, and bears against a coiled spring c¹¹, mounted in the base portion of the channel 55 bar c⁶, as clearly shown in detail in Fig. 7. It will be understood that the plunger c¹⁰, is afforded a vertical movement independent of the spring controlled cushioning movement of the anvil c⁷, for the purpose of enabling the male die to effect a clean crease 60

aided by the female die, without destroying the fibers about the corners of the sheet or board in the creasing and so that the crease throughout formed, will be highly flexible. This is accomplished in the creasing operation by the independent action of the anvil spring cushioning the sheet or board, while the two dies are in pressure contact with the respective surfaces of the sheet or board to form the required crease of the character 70 as above explained, examples of which are fully illustrated in Figs. 8 and 9. The male dies of the respective creasers C and C¹, are carried by cross-bars c¹² and c¹³, 75 slidable in guides c¹⁴ and c¹⁵, provided in the standard A. These cross-bars by ball bearing connections c¹⁶, are connected with plungers c¹⁷, operated by a series of eccentrics c¹⁸, carried by a driven cross-shaft c¹⁹, journaled in the upper part of the standard 80 A. The shaft c¹⁹, is operated by a gear-wheel c²⁰, meshing with an idler gear c²¹, and it in turn meshes with a gear d, mounted on a driven shaft d¹, extending across the machine and journaled to the standard 85 A¹. On the shaft d¹, are mounted a series of eccentrics d², operating plungers d³, which by means of ball bearing connections d⁴, support the cross-bar d⁵, from which projects the male member d⁶, of the side creaser 90 D. The female member d⁷, thereof, is mounted in the standard A¹, but in other respects structurally is the same as the creasers C and C¹, hereinbefore fully described. After the sheet or board 95 C², has been released from the stops a³ and a⁴, it is pressed in traveling over the feed rollers a⁸ and a⁹, by the pressure rollers b¹, until the sheet or board reaches the stops a¹¹ and a¹². The shiftable guide a¹³ in the meantime having 100 been moved cross-wise of the machine by a roller a¹⁴, carried by the cross-bar c¹³, so that when the end of the sheet or board has reached a position to be acted upon by the creasers C and C¹, it will at that moment be in a true alining position to the vertically descending male members c, of the said creasers to be acted upon thereby, to insure a well defined crease in the sheet or board C². The creasers C and C¹, descend 105 alternately to provide by following operations the end creases c⁴⁰ and c⁵⁰, in the sheet or board C², as clearly shown in Fig. 2. The stops a¹¹ and a¹², now release the sheet or board C², and it is carried forward by the revolving rolls a⁸ and a⁹, until reaching the stops a^{14x} and a¹⁵, when the side creaser D, descends upon the sheet or board C², to first 110 form a crease in one side c⁴⁵, Fig. 2, and this creaser D, rises to allow the sheet or board C², to be fed forward until reaching the stops c^{16x} and c^{17x}, when the said creaser D, again descends to form the other side 115 crease c⁵⁵, Fig. 2, in the said sheet or board. The stops a³ and a⁴, move up and down in 120

the guide-ways a^{16} and a^{17} , provided in one side of the female members of the end creasers C and C¹, as clearly shown in Figs. 5 and 10. Motion is imparted to these 5 stops as well as the stops a^{11} and a^{12} , by means of rock-shafts a^{18} , journaled in bearings a^{20} and a^{21} , carried by brackets a^{22} , extending from the guide-ways a^{16} and a^{17} . The said rock-shafts a^{18} are connected by 10 links a^{19} , with the stops a^9 , and a^4 , and a^{11} , and a^{12} , and the forward end of the said rock-shafts have secured thereto depending links a^{30} , carrying rollers a^{31} , operated upon by a bar a^{24} , moved in a vertical direction 15 by means of a chain of links a^{25} , and a bell crank-lever a^{26} , one end of which carries a roller a^{27} , operated upon by a cam a^{28} , mounted on a shaft a^{29} , which is journaled in the standard A. The bell crank lever a^{26} , 20 is journaled to the rock-shaft b , of the front of the machine, which rock-shaft operates the pressure-rolls b^1 , as clearly shown in Figs. 4 and 5. The stops a^{14x} , and a^{15} , and c^{16x} , and c^{17x} , are operated in the guide-ways 25 c^{18x} , and are provided with rock-shafts c^{19x} and c^{20x} , journaled in bearings c^{21} and c^{22} , carried by the standard A¹. The rock-shaft c^{19x} , at one end carries a lever c^{23} , on which is mounted a roller c^{24} , operated upon by a 30 bar c^{25} , movable vertically by a cam c^{26} , journaled to the standard A¹. A bracket c^{27} , extends from the bar c^{25} , and carries a roller c^{28} , which is operated upon by the said cam c^{26} . A coiled spring c^{29} , is attached at one end to the lower end of the 35 said bracket and at the opposite end to the said standard A¹, to maintain the roller c^{28} , in proper contact at all times with the working surface of the cam c^{26} , to thereby insure 40 true vertical alining movement of the said bar c^{25} , to raise and lower the said stops a^{14x} and a^{15} , accordingly.

It may be here remarked that similar brackets and cams are provided at the opposite 45 end of the bar c^{25} , for like purposes. The stops c^{16x} and c^{17x} , are connected with the rock-shafts c^{19x} and c^{20x} , by means of the links c^{30} . The opposite end of the said rock-shaft c^{20x} , has secured thereto an arm c^{31} , 50 carrying a roller c^{32} , resting upon a vertically moved bar c^{33} , as clearly shown in Fig. 14. Secured to each end of the bar c^{33} , are brackets c^{34} , carrying rollers c^{35} , operated upon by cams c^{36} . Springs c^{37} , are attached to the lower ends of the brackets c^{34} , 55 and have their opposite ends attached to the standards A¹, to thereby enable the roller c^{35} , to ride upon the working face of the cam c^{36} , to thus impart true vertical alining movement to the bar c^{33} , for raising and lowering the stops c^{16x} and c^{17x} . The pressure-rolls b^1 , at both end portions of the machine raise and lower to press the sheet 60 or board during its forward movement while the series of between rollers b^2 , serve to

feed the sheet or board forward during its travel through the machine. These rollers are mounted in a box-like trough b^3 , extending lengthwise of the machine and their pressure is adjusted by means of springs b^4 , 70 controlled by thumb-nuts b^5 . A centrally located table b^6 , is provided in the machine to prevent sagging of the sheet or board between the rollers a^8 and a^9 , and the edges of the sheet or board in passage are prevented 75 from upturning by means of the guides b^7 , b^8 and b^9 , as clearly illustrated in Figs. 4, 12 and 14, the guide b^9 , being supported by a bracket b^{10} , secured to the standard A¹. The brackets b^{11} and b^{12} , support the box- 80 like structures b^3 , for the pressure-rolls b^2 , as clearly shown in Figs. 4 and 5.

A belt e , from any suitable source of power passes around loose and fast pulleys e^1 and e^2 , provided with a shifter e^3 . On 85 the shaft e^4 , carrying the loose and fast pulleys e^1 and e^2 , is provided a gear-wheel e^5 , which meshes with the gear d , mounted on the shaft d^1 . This shaft extends across the machine and is provided at its opposite end with a sprocket e^6 , and a chain e^7 , passing around a sprocket e^8 , which is mounted on the shaft e^9 . Said shaft e^9 , is journaled in the standard A¹, and has mounted thereon the cams c^{26} and c^{36} , operating the stops c^{16} 90 and c^{17} , as aforementioned. The shaft d^1 , also has mounted on it the belt-wheel e^{10} , which by means of a belt e^{11} , revolves the wheel e^{12} , mounted on a shaft e^{13} , which latter is journaled to the standard A, and extends across the machine. This shaft e^{13} , 95 also carries similar belt-wheels e^{14} and e^{15} , which by means of belts e^{16} and e^{17} , operate pulleys e^{18} and e^{19} , to revolve the rollers a^8 and a^9 .

The gear-wheel d , meshing with the idler gear c^{21} , revolves the gear c^{20} , to impart motion to the shaft c^{19} , extending across the machine and having mounted on its opposite end the gear e^{20} , meshing with an idler e^{21} , 110 to drive a gear e^{22} , which is mounted on the shaft a^{29} , and the said gear in turn gears with pinions e^{23} and e^{24} . The pinion e^{23} , gearing with a gear e^{25} , and a pinion e^{26} , 115 drives the shaft a^{10} , on which is mounted the two front feed rolls a^9 . The pinion e^{24} , meshing with a series of idler gears e^{27} , and pinions e^{28} , drives the centrally located feed rolls a^9 . The last pinion e^{28} , 120 of the series mounted on the shaft e^{29} , drives the belt-wheel e^{30} , and through the belt e^{31} , and belt-wheel e^{32} , is imparted motion to a shaft e^{33} , which drives one of said rollers a^9 . On the shaft e^{33} , is mounted a pinion e^{34} , 125 meshing with an idler gear e^{35} , to impart motion to a pinion e^{36} , mounted on the shaft e^{37} , to drive the other rear feed roll a^9 , at the discharge end of the machine.

The mode of operation of the machine as 130 hereinbefore described will be explained, as

follows:—The sheet or board C², is fed into the front of the machine against the guide a², and stops a³ and a⁴, and under the guides a⁷, the pressure rolls b¹, at the front of the machine are caused to descend by the cam a²⁸, rocking the shaft b, this presses the sheet or board into firm contact with the revolving feed-rollers a⁹, at the front of the machine and at the same time the stops a³ and 5 a⁴, are withdrawn, allowing the sheet or board C², to freely pass through the machine until the stops a¹¹ and a¹², are reached, by which time the positioning member a¹³, will have operated on the edge of the sheet 10 or board to bring it into a position for the respective creasers C and C¹, in sequence to form alternately descending creases of the character shown in Fig. 9, therein, first in one end portion and then in the other end portion, as shown in Fig. 2. Having thus 15 formed the respective end creases, the stops a¹¹ and a¹², are withdrawn, and the sheet or board is then free to move forward until positioned by momentary contact with the stops a^{14x} and a¹⁵, at which time the creaser D, will descend to form the side crease c⁴⁵, when the creaser D, rises and the stops a^{14x} and a¹⁵, are withdrawn so that the sheet 20 or board may be fed forward by the feed-rolls a⁹, against the stops c^{16x} and c^{17x}, and holding the sheet or board C², long enough 25 to permit the creaser D, to again descend to provide in the said sheet or board the other side crease c⁵³, and of a character of creasing such as shown in Figs. 8 and 9; when the last crease is provided, the stops c^{16x} and c^{17x}, will be withdrawn, and the feed-rollers a⁹, at the rear of the machine 30 will carry the thus creased sheet or board onto the table a¹, for being discharged therefrom into any suitable receptacle therefor. 35

It will thus be observed from the foregoing description the entire momentary following operations in sequence of the machine as above explained, are automatic throughout, and that the sheet or board as it is fed into the machine along the table a, thereof, passes through the machine unaltered or changed as to its plane of travel 40 to receive the respective end and side creases 50

therein in the manner as hereinbefore fully explained.

Having thus described the nature and objects of my invention, what I claim as new and desire to secure by Letters Patent 55 is:—

1. A machine for creasing card or other board, consisting of means located in one part of the machine to automatically crease the board in one end, means in another part 60 of the machine to crease the opposite end without shifting or feeding said board, means to feed the said creased board forward, means to then crease one side, means to feed said board, side creased forward, 65 means to crease the opposite side and thereby to complete the creasings thereof and each successive defined operation effected without shifting said board out of the plane of its travel from the feeding into the machine to the point to permit of its discharge and means to then discharge said board, for being instantly formed into a unit-section. 70

2. A machine of the character described, 75 comprising standards having front and rear tables, the front table having an adjustable guide for the board to be fed, stops located in the front of the machine to position said board during its forward feed and before any creases are formed in the board, means to feed said board forward, creasers positively actuated to alternately crease the board first in one end and then in the other, 80 without shifting or feeding said board and then after being fed forward contacting with supplemental stops located in the rear of the machine to permit a second creaser to alternately crease first one side and then 85 after the board is fed forward to crease the other side and finally means to release said stop so as to permit the thus creased board to be released from the machine. 90

In witness whereof, I have hereunto set my signature in the presence of the two 95 subscribing witnesses.

LEWIS A. MAYALL.
